CLAIM

The ornamental design for a camera with helmet mount, as shown and described.

DESCRIPTION

FIG. 1 is a top, front and left side perspective view of a camera with helmet mount;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is an exploded top, front and left side perspective view thereof;

FIG. 9 is a bottom, rear and left side perspective view thereof;

FIG. 10 is a rear elevation view thereof, shown with the base portion omitted for ease of illustration; and,

FIG. 11 is a bottom plan view thereof.

The broken lines depict portions of the camera with helmet mount that form no part of the claimed design.
